ELECTRICAL APPARATUS

James L. Green, Cleveland, Ohio, and Frederick T. Hicks, Detroit, Mich., assignors to The Indemne Corporation, a corporation of Michigan

Application June 5, 1937, Serial No. 146,614

11 Claims. (Cl. 175—365)

Our invention pertains to electrically operated contactless vibrators and systems for operating and utilizing the same.

It is an object of our invention to provide electro-magnetically operated vibrators which are especially useful as radio B power units for energizing luminous signs, producing musical tones, and musical notes, as frequency standards and for many other applications requiring long life and permanent adjustment by eliminating mechanically engaging contacts with the accompanying wear, clatter, corrosion, and arcing.

It is also an object of our invention to provide a contactless vibrator actuated by a coil of 15 a conductive metal which varies its resistance in accordance with the intensity of the electromagnetic field in which it is exposed.

It is a further object of our invention to provide such a contactless vibrator having means 20 for periodically varying the field intensity comprising an armature member which is moved by the flux from the winding for pulsating the field in which the winding is exposed.

Another object of our invention is to provide 25 such a contactless vibrator wherein the field structure comprises a core and an enclosing shell arranged to define series connected air gaps and having the energizing winding disposed adjacent one of the air gaps and the armature adjacent the other air gap.

A further object of our invention is to provide such a contactless vibrator comprising a current inverter for inverting from direct current.

The novel features which we consider characteristic of our invention are set forth with particularity in the appended claims. The invention itself, however, both as to its organization and its method of operation, together with additional objects and advantages thereof, will best 40 be understood from the following description of specific embodiments, when read in connection with the accompanying drawing, in which:

Fig. 1 is a longitudinal sectional view showing the construction of the contactless vibrator;

Fig. 2 is a diagrammatic view representing the device in connection with associated circuits for operating and utilizing the same;

Fig. 3 is a longitudinal sectional view showing another embodiment of the vibrator;

Fig. 4 is an elevational view of the armature support; and

Fig. 5 is a diagrammatic view showing a system utilizing the device.

Referring more particularly to Fig. 1 of the drawing, our contactless vibrator comprises a

shell 1 which is of iron or other ferro-magnetic material of low magnetic reluctance, of cast or sheet construction. The shell 1, which is preferably of circular cross-section, is provided at one end with an enlarged annular collar 3 for receiving and supporting a cap 5 of magnetizable material. The collar 3 is precisely tapered and ground to fit snugly into an annular recess 7 in the edge of the rim 9 of the cap in order to provide a close coupled magnetic joint. The outer surface of the collar 3 is threaded for cooperatively engaging the outer wall of the recess 7 in the cap, which is suitably threaded. The cap is thus firmly secured on one open end of the shell 1, where it is a closure and serves to 15 continue the magnetic flux path.

A pole 11 of magnetizable material is mounted on the inside of the closed end of the cap and it extends into the shell to continue the low reluctance flux path therein. The pole 11 is substantially flat at its inner end, and it may be integral therewith, or secured thereon as by welding for example.

An armature 13 is movably supported adjacent the inner end of the pole 11 on a spring support 15 which is clamped between the outer end of the shell and the cap. The armature support comprises a flat resilient diaphragm like member, preferably non-magnetic, with apertures to minimize air damping. The armature 30 is secured to the support in any suitable manner as by riveting, and opposite sides of the armature are of unlike conformations. As shown, the inner side of the armature 13 is a tapered cone like conformation which is cut off flat at the inner end like a truncated cone, for a purpose to be subsequently described. The shape, size and weight of the armature and the rigidity of its support may be suitably selected for predetermining its vibrating frequency.

Enclosed and supported by the shell 1 is a core 19 which is provided with an electrically conductive coil or solenoid winding 21, for magnetizing the field structure of the vibrator. The core 19 is covered with a layer or tube 23 of insulating material and insulated conductor is wound thereon. The coil is held together and secured in place by means of suitably insulated annular disks 25 in the usual manner. A flange 27 projects inwardly in the shell for abutting and holding the inner end of the coil when it is inserted into the shell. The terminals 28 of the coil 21 are extended from the shell through suitable bushings 30 in the side wall of the shell 1 as will be understood.

Although the coil or solenoid winding may be wound on the core and secured in the usual manner, the electrical conductor which comprises the coil is made of a special metal that provides an important characteristic in the operation of the contactless vibrator, as will subsequently be more fully set forth.

The end of the core 19 adjacent the armature is provided with a conical recess 29 similar in conformation to the adjacent side of the armature which moves therein.

At its other end the core 19 is recessed axially to receive a pin 31 projecting from a plug 33 of brass or other non-magnetic material. Being of a cross section similar to the core 19, the non-magnetic plug 33 fits into the coil 21 where it serves to secure the outer end of the core spaced from the end of the coil. The plug 33 is on a closure disk 35 which closes the end of the shell 1 in which it is preferably secured by external threads engaging corresponding threads on the inside of the shell. The disk 35 is also made of non-magnetic material in order to provide an appreciable air gap for the magnetic flux to pass through the turns of the winding 21 between the adjacent ends of the core 19 and the shell 1.

It will be seen that the field structure of our contactless vibrator comprises the shell 1, cap 5, pole 11 and core 19 which together define a low reluctance flux path having two air gaps in series relation as at A and B. The armature 13 is disposed in one of the air gaps, at A and it is so mounted that it can move axially therein.

Because of its unlike conformation on opposite sides, corresponding to the adjacent field structure, and because of its interfitting relation the movement of the armature 13 toward the core 19 increases the total air gap, and reverse movement decreases the total air gap.

Because of the disposition of the solenoid winding 21 around the second air gap B, the coils of the winding are exposed to the varying flux passing between the adjacent ends of the core and the shell.

For winding the magnetizing coil, an electrical conductor is provided of metal which varies its resistance according to the intensity of the electromagnetic field to which it is exposed. Such electrical and magnetic properties are found in cadmium, bismuth, zinc, silver and other metals and alloys in which the resistance increases when the intensity of the electromagnetic field is increased. Such metals we term "ohmomagnetic". In our contactless vibrator we expose a coil of such ohmomagnetic material, in the second air gap B which provides the maximum exposure to the varying flux. For this purpose we preferably use bismuth, either pure or alloyed. At times it is necessary to make only a part of the coil of bismuth in order to limit the resistance in accordance with the applied D. C. voltage. The frequency of vibration of the armature is influenced by the inductance and magnetic lag of the coil as well as by the percentage of ohmomagnetic material.

In use the solenoid winding 21 of the vibrator is connected by input conductors 37 and 39 for energization from a source of direct current such as a battery 41. A high inductive impedance such as a choke coil 43 may be connected in series with one conductor 39 of the energizing circuit. If the vibrator is to be utilized as an inverter for converting a portion of the direct current to an alternating or pulsating current, output conductors 45 and 47 are connected from op-

posite ends of the energizing winding 21, or tapped from intermediate turns.

To restrict the direct current from the output circuit, and for energizing the circuit in accordance with the pulsating component of the energizing current, a condenser 49 is inserted in one output conductor. If the vibrator is to be utilized for supplying only a potential for modulating purposes the condenser may be quite small, but if it is to be utilized to supply a substantial current for power purposes the condenser must be selected of a suitable size. Transformers or other output arrangements may be utilized if desired.

In operation, the current is turned on to energize the coil 21 and to magnetize the core 19. Electromagnetic flux is thus induced to flow through the field structure of the vibrator passing across the air gap A to the pole 11, thence through the cap 5, through the shell 1, and returning from the other end of the shell to the other end of the core by passing through the surrounding air gap B and the adjacent turns of the coil. The armature is then moved toward the pole 11 extending from the cap. This happens because of the tendency of magnetic loops to shorten their length, and because of the peculiar shape of the armature 13 it moves away from the core 19 and toward the pole 11 to shorten the air gap.

Because of its peculiar non-uniform shape, the movement of the armature toward the pole 11 decreases the total air gap, as previously described. This decreases the reluctance of the flux path and increases the flux. But increasing flux also increases the density of the field, to which the coils of the energizing winding are exposed in the air gap, and this in turn increases the ohmic resistance of the winding, which is of an ohmomagnetic material, as previously set forth. This decreases the energizing current in the winding and the armature 13 falls back from the pole 11 toward the core because of the resilience of its support.

Movement of the armature away from the pole 11 increases the total air gap A and increases the reluctance of the flux path, as previously set forth. This causes the flux to decrease which diminishes the field intensity to which the energizing winding is exposed in the air gap B around the left hand end of the core. The resistance of the winding 21 is thus decreased and it takes a greater energizing current. The flux now increases and the armature is again drawn toward the pole 11 as previously described.

This sequence of operations constitutes a cycle which is repeated periodically with such rapidity that the armature is caused to vibrate. The growing and collapsing of the field induces an alternating current in the energizing winding which may be tapped off by an output circuit as disclosed. Also the winding may be provided with various output taps to provide induced alternating current of any desired potential.

In accordance with another embodiment of our invention, as shown in Fig. 3, two coils 51 and 53 may be mounted in end-to-end relation for defining an air gap C between the cores 55 and 57 which are disposed in axial alignment. The right hand coil 51 is wound with ordinary copper wire and the left hand coil 53 is wound with a conductor of bismuth or other ohmomagnetic material. The two coils may be selected in various ratios of resistance, turns, and the like according to the operating characteristics desired and

they are wound and secured upon the cores in the usual manner. Desirable operating characteristics for current inverter use are obtained by providing about ten per cent greater ampere turns on the left hand coil 53 than on the copper coil 51. A slack conductor 54 connects adjacent ends of the coils 51 and 53.

The inturned ends of the cores are respectively square and conically recessed, as in the first embodiment. At its outer end, the right hand core 51 is integral or joined on the closed end of a cup shaped shell 59 which is provided with a threaded coupling collar 61 around its open end. The outer end of the left hand core 53 is apertured to firmly receive a pin 63 projecting from a plug 65 of non-magnetic material. The outer end of the non-magnetic plug 65 is provided with a reduced portion 67 which is threaded for securing in the closed end of a cup shaped shell 69 which has a threaded collar 71 around its open edges.

The shells 59 and 69, which enclose and support their respective solenoids, are of any suitable ferro-magnetic material and they are firmly joined together around their open edges by a coupling sleeve 73 which is internally threaded for clamping the coupling collars. The sleeve 73 is also of ferro-magnetic material and serves to provide a joint of low magnetic reluctance. The armature 13, similar to that previously described, is supported around its outer edges in an annular recess 75 in the abutting edges of the shells whereby it is disposed in the air gap C between the inner ends of the cores, and as in the first embodiment the armature diaphragm has apertures to minimize damping. Interconnecting conductor 54 is passed through one of the apertures, as shown in Fig. 4.

A terminal conductor 77 extends from the outer end of the ohmomagnetic coil 53 through a suitable bushing 79 in the side wall of the shell. From the outer end of the copper coil 51, and also from an intermediate turn, a terminal conductor 81 and an intermediate tap 83 are respectively connected passing through suitable insulating bushings 85.

In operation the terminal conductor 77 from the ohmomagnetic coil 53 is connected to a direct current source, such as the battery 87, as shown in Fig. 5. The intermediate tap 83 from the copper coil 51 connects to the other side of the battery 87.

To energize an output circuit in accordance with the pulsating component of the input current, the terminal conductor 81 may be connected through a condenser 89 to an out-put conductor 90. The other output conductor 91 is connected from the terminal conductor 77 of the other coil.

This embodiment of our invention operates in a manner substantially similar to the operation of the first embodiment which was previously described and will not be repeated.

In the operation of this embodiment the auto-transformer action provides a higher out-put voltage in proportion to the input voltage. Also, copper coil shells may be provided having different tap connections, resistance, and ampere turns for convenient replacement and attachment to the ohmomagnetic half of the unit.

By eliminating mechanically striking contacts and operating our device in the manner disclosed, the vibrator is free from mechanical wear, sparking and corrosion which would change its adjustment and shorten its life. Also disturbing influences are eliminated such as the noise caused

by the mechanical striking of contacts and electro-magnetic disturbances caused by sparking. The vibrator is free to move with a pure simple harmonic motion, as determined by the weight and elasticity of the armature, as well as the inductance of the coil and other factors; as previously set forth our contactless vibrator is especially useful as a radio B supply unit, in luminous sign lighting, as a frequency standard or modulating device and for all purposes where long life and permanent adjustment are important.

We do not wish to be restricted to the specific structural details, of parts or circuits herein set forth, as various modifications thereof may be effected without departing from the spirit and scope of our invention.

We claim:

1. A contactless vibrator comprising, a field structure of magnetizable material defining an electromagnetic flux path of low reluctance having an air gap therein, an electrical conductor of ohmomagnetic material disposed for energizing said field structure and exposure to the flux therefrom, and an armature of magnetizable material movable for varying said air gap and responsive to the flux therein.

2. A contactless vibrator comprising, a field structure of magnetizable material having air gaps therein, an electrical conductor of ohmomagnetic material disposed adjacent one of said air gaps for magnetizing the field structure and exposure to the flux therefrom, and an armature movable adjacent the other air gap for decreasing the total air gap in response to increasing flux.

3. A contactless vibrator comprising, a core of ferro-magnetic material, a shell of ferro-magnetic material arranged for supporting and enclosing said core and defining a flux path having air gaps therein, a core energizing winding of ohmomagnetic material adjacent one of said gaps, an armature of magnetizable material adjacent the other air gap for decreasing the total air gap in response to increasing flux, and a resilient support for movably supporting said armature.

4. A contactless vibrator comprising, a field structure of ferro-magnetic material having air gaps therein, an electrical conductor of bismuth disposed adjacent one of said air gaps for magnetizing the field structure and exposure to the flux therefrom, and a magnetizable armature movable adjacent the other air gap for varying the total air gap in response to the varying flux density therein.

5. A contactless vibrator comprising, a magnetizable structure having an air gap, the portions of the field structure on opposite sides of said air gap being of unlike conformation, an electrical conductor for magnetizing said field structure, an armature member of unlike conformation on opposite sides corresponding to the unlike conformations of the portions of the field structure spaced adjacent said air gap, and resilient means for movably supporting said armature adjacent the air gap with its unlike conformations toward the field structure surfaces of corresponding conformation.

6. A contactless vibrator comprising, a core of ferro-magnetic material, a winding of ohmomagnetic material for energizing said core, a shell of ferro-magnetic material enclosing said core, a ferro-magnetic cap secured on one end of said shell, a ferro-magnetic pole extending from said cap into said shell in spaced relation to define an air gap at the adjacent end of said core, and the

- spaced ends of said core and said pole being of unlike conformation, an armature disposed in said air gap, said armature being of unlike conformation on opposite sides corresponding to the 5 unlike conformations of the spaced core and pole defining the air gap, and resilient means for movably supporting the armature in said air gap.
7. A contactless vibrator comprising, a pair of cores of ferro-magnetic material, an enclosing 10 shell of ferro-magnetic material for supporting said cores in spaced end-to-end relation with an air gap therebetween, a winding of copper conductor on one of said cores, a winding of bismuth on the other one of said cores, an armature movable 15 in response to magnetic flux from said cores for varying the total air gap, and means for movably supporting said armature adjacent the air gap.
8. In combination, a solenoid winding of ohmo- 20 magnetic material, a source of direct current, a circuit for energizing said winding from said source, a field structure having a flux path magnetized by said winding, and means for varying the reluctance of said path to subject said winding to a varying flux for varying the resistance 25 of said winding in said circuit.
9. A contactless vibrator system comprising, a solenoid winding of ohmomagnetic material, a source of direct current, a circuit for energizing 30 said winding from said source, a field structure having a flux path magnetized by said winding,

and an armature responsive to flux in said path for periodically decreasing the reluctance of the path whereby the varying flux varies the resistance of the winding and the armature vibrates.

10. A current inverter system comprising, a field structure providing a low reluctance flux path, a winding of bismuth for magnetizing said field structure, a source of direct current, an input circuit for energizing said winding from said source, means for periodically varying the reluctance of the flux path to pulsate the energizing current, an output circuit, and means for energizing said output circuit in accordance with the pulsating component of said energizing current. 10

11. A current inverter system comprising, a field structure providing a low reluctance flux path, a winding of ohmomagnetic material for magnetizing said field structure, a source of direct current, an input circuit for energizing said winding from said source, an armature responsive to the flux for varying the reluctance of the flux path, said armature moving to decrease the reluctance of the flux path in response to increasing flux whereby the armature moves periodically, 25 an output circuit, and means for energizing said output circuit in accordance with the pulsating component of said energizing current. 20
